UNITED STATES PATENT OFFICE.

CARL G. HARSTRÖM, OF PEEKSKILL, NEW YORK.

WATCH-CASE SPRING.

SPECIFICATION forming part of Letters Patent No. 376,524, dated January 17, 1888.

Application filed February 23, 1887. Serial No. 228,605. (No model.)

To all whom it may concern:

Be it known that I, CARL G. HARSTRÖM, a citizen of the United States, residing at Peekskill, in the county of Westchester and State of New York, have invented a new and useful Improvement in Watch-Case Springs, of which the following is a specification.

My invention relates to that class of watch-case springs which consist of two parts—*i. e.*, a spring of wire supported in a rigid holder, and has for its object the overcoming of mechanical difficulties that have made such springs either as unreliable as the old forms of springs or unprofitable to manufacture. I attain the object by the means illustrated in the accompanying drawings, in which similar letters refer to similar parts throughout the several views.

Figure 1 represents my spring attached to a watch-case. Fig. 2 is a view of the bottom edge of the spring-holder. Fig. 3 is a view of the outer side of the holder. Fig. 4 represents cross-sections of the spring and holder.

My spring consists of a holder, B, made, preferably, of steel, in sizes to suit the various forms of watches. Its outer circumference is provided with the solid projection d and the slotted projections c and b, as shown in Figs. 1, 2, 3. Heretofore the projections c and b have been made solid, with holes drilled longitudinally through them for the introduction of the spring D therein. The difficulty and expense attendant upon the drilling of the said holes have practically made the manufacture of the springs a failure commercially. Instead, therefore, of drilling these projections c and b, I cut slots through them, as shown in Fig. 3 and sectional Fig. 4.

The spring D, I make, preferably, of piano-wire, although any good hard-drawn steel or elastic wire may be used for the purpose. The wire is reduced to a semicircular form, as shown in cross section, Fig. 4, and the bottoms

of the slots, through c and b, are adapted to the form of the spring. 45

When the spring D is set in its place within the slots c and b, pressure is applied to the projections and they are closed over the spring, as represented at e in the cross-section, Fig. 4. The projections are made to embrace the spring closely, but with a pressure that will admit of the longitudinal adjustment of the spring—that is, referring to Fig. 3, in which the spring is represented by dotted lines D, when the projections c and b are closed over the spring 55 the spring may still be moved between them from right to left. When the spring D is thus secured in its place, the projections b and c, with the solid projection d, form a bead that fits within a groove that is made within the 60 edge of the watch-cases. A screw secures the holder B in the case, as at a, Fig. 1. The holder B being thus held firmly in place, the wire D is as rigidly secure, and the torsional strain put upon the spring by means of the 65 pressure on the spring-point f, Fig. 1, gives the spring-power for operating the lid of the watch-case.

Having described my invention, what I desire to claim, and secure by Letters Patent, is— 70

1. In a watch-case spring, the combination of a spring, D, and a spring-holder, B, provided with projections c c and b b, bent over upon the spring, holding said spring firmly in its place yet admitting of its lateral adjustment. 75 substantially as herein shown and described.

2. The combination, in a watch-case spring, of a wire spring, D, semicircular in cross-section, and a holder, B, having projections c c and b b bent over upon the spring to secure it 80 in place, substantially as herein shown and described.

CARL G. HARSTRÖM.
